UNITED STATES PATENT OFFICE.

JAMES M. H. SPOONER, OF DETROIT, MICHIGAN.

INCUBATOR.

SPECIFICATION forming part of Letters Patent No. 508,492, dated November 14, 1893.

Application filed March 31, 1893. Serial No. 468,614. (No model.)

To all whom it may concern:

Be it known that I, JAMES M. H. SPOONER, a citizen of the United States, residing at Detroit, in the county of Wayne, State of Michigan, have invented certain new and useful Improvements in Incubators; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in incubators, and consists in a certain construction and arrangement of parts, as hereinafter fully set forth, the essential features of which are pointed out particularly in the claim.

20 The objects of the invention are, to produce an incubator of simple construction, in which a perfect circulation of the heating agent is attained thereby insuring a uniform temperature in all parts of the incubatory chamber 25 during the period of incubation, and in which provision is made for automatically regulating said temperature.

20 The objects are attained by the mechanism illustrated in the accompanying drawings, in 30 which—

Figure 1 is a general perspective view of the incubator, with the outer door swung down. Fig. 2 is an enlarged vertical section through the incubator, and the heating apparatus. 35 Fig. 3 is an enlarged perspective of the heating apparatus. Fig. 4 is a vertical transverse section through the incubator.

Referring to the letters of reference, A designates a suitable case or cabinet having the 40 incubatory chamber B, access to which is afforded, through the outer hinged door C, and the inner glass door C', shown in Fig. 1. Upon the bottom of said chamber are the moisture pans D, and above said pans are supported the 45 trays E, that are adapted to contain the eggs.

Located in the top of the cabinet is a water tank F, which forms the ceiling of chamber B.

G designates a heating drum which is secured to one end of the cabinet, and provided 50 with a central vertical flue therethrough. The lower end of said drum is formed slightly tapering, and is adapted to receive the burner

of a lamp G', which is supported upon a swinging bracket h. The body portion of said drum is hollow being formed of double walls with 55 a water space g, between them, as shown in Fig. 2. The inner wall i, inclines slightly inward thereby reducing the opening through the drum at its upper end. The cap portion of the drum is provided with a water space H, 60 which is separated from the space g in the body of the drum by an interposed air-space H', which extends across the diameter of the drum and is provided with perforations a, which afford sufficient ventilation to properly 65 sustain the flame of the lamp. The central opening or flue through the drum is continued through the water section H, the upper end of said flue being covered with a conical hood I, having an opening at its apex. 70

Located in the water tank F, are two independent sinuous pipes J, that traverse said tank longitudinally, and are immersed in the water therein when said tank is filled. These pipes are open at each end, their outer ends 75 communicating with the water-space H in the heater, and their inner ends with the interior of said tank, as shown in Figs. 2 and 3. The outer ends of said pipes J pass out of the tank through a partition b, which separates the water in the tank F, from the water in the closed chamber K, which is interposed between said tank and the water space H, with which latter said chamber communicates. The inner ends of said pipes discharge into said tank at 80 a point farthest from the heater, whereby the water in said tank is maintained at a uniform heat. Communicating with the end of the tank F, adjacent to the heater, is a pipe L, which extends obliquely downward, and discharges into the base of the water-space g in 85 said heater. Some distance above said pipe and running parallel therewith, is a second pipe M, which connects the water space g of the heater with the water-chamber K. It 90 will be apparent, that, by means of the construction above described, the water in space H of the heater, will become more quickly heated because of the concentration of heat at that point, caused by arresting the caloric 95 current through the contraction of the central flue at its upper end. The water, so heated, flows out through the pipes J, and traversing 100 said pipes, discharges into the water in tank

F, as before stated. To supply this flow, the return water from the tank passes downward through pipe L, to the water space g in the heater, and becoming heated, flows upward 5 through pipe M to the chamber K, and out of said chamber into the upper water space H, thence out through the pipes J, thus making a complete circulation.

The temperature of the incubatory chamber 10 B is regulated by means of a damper c, located in the ventilating flue O, clearly shown in Figs. 2 and 4. Said damper is pivotally mounted in said flue, and is provided with a weighted arm d, which normally holds said damper 15 closed. Crossing the interior of said chamber is a non-expansible bar P, upon which is supported a strip of metal e, highly susceptible to changes of temperature. This strip of metal, is firmly secured at each end, but is free 20 at its center, at which point it is coupled to a lever f, pivoted to the bar P, the opposite end of said lever being coupled to a rod i, which is attached to the damper c. By this arrangement, should the heat in the chamber B be- 25 come too great, the expansion of the strip e will cause it to buckle at the center, and actuate the lever f so as to draw upon the rod i and open the damper c. The falling of the temperature in the chamber B, caused by the es- 30 cape of the warm air through the ventilator, causes the metal strip e to contract and release the lever f, when the weighted arm d will close said damper.

R designates an induct port, to provide for filling the system with water, and s is an air 35 vent to permit of the escape of air as said system is filled.

It will now be apparent, that, with but slight expense for fuel, an incubator of this construction, can be operated so as to maintain 40 the same degree of heat in all portions of the incubatory chamber, thereby insuring a perfect result in the hatching of the eggs.

Having thus fully set forth my invention, what I claim as new, and desire to secure by 45 Letters Patent, is—

In an incubator, the combination of the heater having the upper and lower water sections, the water chamber K communicating with said upper section, the water tank, the 50 partition dividing said tank from said chamber, the independent pipes in said tank, said pipes passing through said partition and communicating at one end with the upper water section, the other end of said pipes discharging into said tank, the pipe connecting the lower water section of the heater with said tank, and the pipe connecting said section with the chamber K.

In testimony whereof I affix my signature in 60 presence of two witnesses.

JAMES M. H. SPOONER.
